UNITED STATES PATENT OFFICE.

JOHN R. JOHNSON, OF GREENWICH, CONNECTICUT.

FIRE POT.

Application filed May 22, 1925. Serial No. 32,054.

In oil burning installations employed for domestic heating purposes, the fuel is burned in a "fire pot" mounted to receive the discharge of the burner. This pot is usually partly closed over by a lining ring of refractory material which confines the flame to a certain extent and acts to direct the blaze against the heat absorbing walls of the boiler. This confinement and concentration of the flame results in an intense heating of the pot, causing it to chip, flake and crack. These injurious effects are accentuated by the alternate cooling and heating following the shutting off and turning on of the burner with the action of the thermostatic control, usually provided. As the fire pot is usually sealed in the boiler and is partially covered over with the lining ring, these injuries or defects in the pot may not become known until an accident occurs. Thus in the case of a cracked fire pot, if after a period of rest, the burner should fail to ignite, the oil discharged from the boiler, instead of collecting in the fire pot and draining back to operate the safety shut-off, will simply leak through the break in the pot and collect in the fire box, where it may burn or explode when ignition is later attempted.

It is to cure the above dangers and defects that my present invention is directed.

This is accomplished in a comparatively simple but practical way by providing a jacket about the fire pot and circulating a cooling fluid therethrough.

In the present disclosure, water or steam is used as the cooling medium and a further novel feature of the invention consists in utilizing this medium either for the purpose of returning heat to the boiler or for heating the domestic water supply.

Additional novel features of the invention will appear as the specification proceeds.

In the accompanying drawing, one practical embodiment of the invention is illustrated, but it should be understood that the structure and modes of use may vary without departure from the spirit and scope of the invention as hereinafter defined and broadly claimed.

Figure 1 is a broken perspective view of the fire pot, as installed with a burner of approved type and connected for use either as a water heater or as a "booster" for the furnace.

Figure 2 is a vertical sectional view of

the fire pot in its relation to the burner head.

Figure 3 is a horizontal sectional view of the fire pot as on substantially the plane of line 3—3 of Figure 2.

In the particular installation shown, the fire pot, indicated generally at 5, has a front opening 6 for the reception of the burner head 7 and side openings 8 for the branches 65 9 of the air duct 10. As usual in burners of this type, the air entering the fire pot through the passes 11, mingles with the discharge from the burner head and burns within the bowl of the pot. The side walls 70 of this bowl are convergent or overhanging as indicated at 12 so as to exert a confining effect, promoting more complete combustion. Combustion is further controlled and promoted by the lining ring 13 of refractory 75 material which seats within a flange 14 and has convergent inner walls 15 forming in effect a continuation of the overhanging walls of the bowl.

The mouth 16 of this ring is sufficiently 80 restricted to hold the flame under control and direct it against the heat absorbing interior walls of the boiler 17. The bottom of the pot is shown as inclined to the center at 18 to collect the oil which may not be 85 ignited and drain the same back through piping 19 to the drip pan 20 which operates to rock the shut-off, the latter parts not being shown in detail because used in present well known installations.

The bowl portion of the fire pot is shown as entirely surrounded by a wall 21, forming a jacket or space 22 surrounding the pot and providing a chamber for holding or circulating a cooling medium. The side 95 portion of this outer wall is shown in Figure 2 as substantially cylindrical and as projecting slightly beyond the lining ring flange, forming with the inwardly inclined side wall of the bowl, a widened portion 23 100 in the upper part of the cooling jacket. A maximum cooling space is thus provided without materially increasing the overall dimensions of the fire pot and without interfering with the connection of the fire pot 105 to the burner head and air flues. In this illustration the cooling jacket stops short of the front end of the fire pot so as to leave the usual attachment flange 24 free to receive the bolts by which the pot is usually 110 mounted.

An inlet and an outlet for the cooling

fluid are provided in the present instance in opposite sides of the jacket wall at 25 and 26 respectively and as a liquid is used as the circulating medium, the inlet is lower than the outlet so as to promote a natural circulation. If air is used as a circulating medium, suitable piping for the purpose may be connected with such inlet and outlet and may be forced under pressure by a branch taken off from the air conduit 10 for instance.

In Figure 1 there is illustrated the possibility of using the fire pot either as a hot water heater or as a means for "boosting" or returning heat to the boiler. The piping for this purpose comprises a section 27 connected with a water main 28 and having a branch 29 in communication with the lower portion of the boiler with valves at 30 and 31 controlling the water line and boiler connection respectively, for the inlet side; the outlet piping comprising a section 32, 33 leading to a hot water tank 34 and a branch 35 extending back to the top of the boiler, the hot water feed and boiler return connections respectively being governed by valves 36, 37.

In this particular embodiment it will be seen that if the valves 30, 36 are closed and the valves 31, 37 are open, water or steam from the boiler will be passed through the jacket of the fire pot and by a natural flow will be returned back into the boiler. On the other hand, if valves 31, 37 are closed and valves 30, 36 are opened, water from the main will be permitted to flow through the jacket of the fire pot and then on into the tank. In either event the fire pot will be cooled sufficiently to prevent scaling, cracking or warping of the same and this flow will have a tendency to maintain the fire pot at a temperature favorable for re-ignition of the fuel each time the burner is started after a shut-off period. The jacket

about the fire pot is an extra safety feature, providing in case of a defect in the bowl of the pot, a receiver for catching any unconsumed fuel.

What is claimed is:

1. The combination with a burner, of a fire pot positioned to receive the discharge of said burner, a cooling jacket surrounding the bowl of such fire pot, a boiler heated from said fire pot, means for circulating fluid from the boiler through the cooling jacket of the fire pot and back into the boiler, a hot water storage system connected with the cooling jacket and means for selectively controlling connection of the jacket with the boiler and with the hot water storage system.

2. A fire pot for oil burners constructed as a unit separate from and independent of the burner structure comprising a flame confining bowl adapted for mounting in the combustion chamber of a furnace as a unit independent of the furnace structure, said bowl being open in the side thereof to admit the combustion supporting air and the flame of a burner directed into the bowl but being otherwise closed about the sides and bottom of the bowl and open at the top, a jacket surrounding the bowl of the fire pot, said jacket extending about the sides and across the bottom of the bowl and thus forming a surrounding chamber, said chamber having no communication with the interior of the bowl and means for enabling the circulation of a heat absorbing fluid within said closed chamber whereby the bowl of the fire pot is kept at a proper operating temperature when the burner is on and a measure of the heat is retained in the fire pot when the burner is off.

In witness whereof, I have hereunto set my hand this 21st day of May, 1925.

JOHN R. JOHNSON.
